UNITED STATES PATENT OFFICE.

KOLMEN OSWALD, OF NEW YORK, N. Y.

KEYHOLE GUARD.

1,076,696.

Specification of Letters Patent.

Patented Oct. 28, 1913.

Application filed July 17, 1912. Serial No. 709,978.

To all whom it may concern:

Be it known that I, KOLMEN OSWALD, a Hungarian citizen, and a resident of New York, in the county of New York and State 5 of New York, have invented certain new and useful Improvements in Keyhole-Guards, of which the following is a specification.

My invention relates to key-hole guards, *i.e.*, devices normally closing a key-hole but 10 adapted to be pressed aside automatically when a proper key is introduced into such key-hole.

My improved key-hole guard is particularly intended to be applied to watchmen's 15 clocks, and is so shown in the accompanying drawings; but the said guard is also adapted for use in many other connections, for example, for use in connection with locks of various kinds.

20 My invention comprises a novel and improved key-hole guard, which normally closes a key-hole but is adapted to be pushed aside automatically by a proper key introduced into such key-hole.

25 The object of my invention is to provide an improved and simplified key-hole guard, readily applied to the cases of watchmen's clocks, and other key-actuated mechanism, which guard shall be actuated automatically 30 by a proper key as the latter is introduced into the clock or other key-actuated device.

I will now proceed to describe my invention with reference to the accompanying drawings and will then point out the novel 35 features in claims.

In the drawings: Figure 1 shows a side elevation of the case of a watchman's clock having my improved key-hole guard applied thereto. Fig. 2 shows a horizontal section of 40 the case of such clock and of the recessed guard plate within which the improved guard is partly contained. Fig. 3 is a transverse section of the clock-case showing the inner side of the guard and the spring which 45 actuates that guard. Fig. 4 shows another section of the clock case, this view being taken on the section line $x-x$ of Fig. 2. Fig. 5 shows a side view of a key provided at its end with a beveled surface for actuating 50 the key-hole guard; and Fig. 6 is another side view of the key, taken from the left of Fig. 5. Fig. 7 shows a detail elevation of the guard plate.

I do not in these drawings illustrate the 55 clock-work or key actuated mechanism of a

watchman's clock, as these features form no portion of the present invention.

In the drawings, 1 designates the case of the clock, and 2 the cover thereof.

44 designates a recessed guard plate secured to the exterior of the clock case, within the recess 43 of which guard plate the key-hole guard, 42, is mounted, said guard being normally in the position shown in Fig. 2, in which position it closes the key-hole 37. This key-hole guard is provided, within the clockcase, with a flanged portion 45 arranged to be guided by the clock case 1; said guard working in a slot 46 of the clock case. A spring 47 tends to hold the guard 65 plate 42 closed normally. The guard is provided with a beveled surface 48 which will be engaged by the end of a proper key, when that key is introduced into the key-hole, such key then pushing the key-hole 70 guard aside so as to permit the full introduction of the key. Figs. 5 and 6 illustrate such a key, 24, said key having at the end a beveled surface 49 which engages the beveled surface 48 of the key-hole guard when 75 such key is introduced into the key-hole.

What I claim is:—

1. The combination with a member having in it an aperture and having a guide slot for a guard for said aperture, of a guard 85 for said aperture having a flanged portion on one side of said apertured member, and having a rib projecting through said guide slot, said rib provided with an inclined face, normally in line with said aperture and 90 adapted to be engaged by a key inserted to enter said aperture.

2. The combination with a member having in it an aperture and having a guide slot for a guard for said aperture, of a guard for 95 said aperture having a flanged portion on one side of said apertured member, and having a rib projecting through said guide slot, said rib provided with an inclined face, normally in line with said aperture and 100 adapted to be engaged by a key inserted to enter said aperture, and spring means tending to hold said guard in position to cover said aperture.

3. The combination with a member having in it an aperture and having a guide slot for a guard for said aperture, of a guard for said aperture having a flanged portion on one side of said apertured member, and having a rib projecting through 105 110

said guide slot, said rib provided with an inclined face and a recessed guard plate in front of said apertured member, and having its aperture in line with the aperture of said member, and having a recess in which the said rib may work.

4. The combination with a member having in it an aperture and having a guide slot for a guard for said aperture, a guard for said aperture having a flanged portion on one side of said apertured member, and having a rib projecting through said guide slot, said rib provided with an inclined face, and a recessed guard plate in front of said apertured member and having its aperture in line with the aperture of said member, and having a recess in which the said rib may work, the inclined face of said rib being normally in line with the aperture of said guard plate, of an instrument adapted to be inserted through said apertures of said guard plate and apertured members, and having an inclined surface adapted to engage the inclined surface of said rib when so inserted, and thereby to press said guard aside.

5. The combination with a member hav-

ing in it an aperture and having a guide slot for a guard for said aperture, a guard for said aperture having a flanged portion 30 on one side of said apertured member, and having a rib projecting through said guide slot, said rib provided with an inclined face, a recessed guard plate in front of said apertured member and having its aperture in 35 line with the aperture of said member, and having a recess in which the said rib may work, the inclined face of said rib being normally in line with the aperture of said guard plate, and a spring tending to hold 40 said guard in line with said aperture, of an instrument adapted to be inserted through said apertures of said guard plate and apertured members, and having an inclined surface adapted to engage the inclined surface 45 of said rib when so inserted, and thereby to press said guard aside.

In testimony whereof I have signed this specification in the presence of two subscribing witnesses.

KOLMEN OSWALD.
